UNITED STATES PATENT OFFICE.

ALBERT C. TERRELL, OF GRAND RAPIDS, MICHIGAN.

DESIGN FOR METAL MOLDING.

47,309.

Specification for Design.

Patented May 4, 1915.

Application filed July 6, 1914. Serial No. 850,018. Term of patent 14 years.

To all whom it may concern:

Be it known that I, ALBERT CLARK TERRELL, a citizen of the United States, residing at Grand Rapids, in the county of Kent and State of Michigan, have invented a new and original Design for Metal Moldings, Designed Especially for Use in the Construction of Metal Furniture, of which the following is a specification.

The single figure shown is a perspective of the molding.

The offsets *a* and *b* are designed to throw

the face of the molding out in relief and thus produce an ornamental effect.

What I claim as new is:

The ornamental design for metal molding shown and described.

Signed at Grand Rapids Michigan July 2, 1914.

ALBERT C. TERRELL.

In presence of—

JOHN W. HILDING,
I. J. CILLEY.
